UNITED STATES PATENT OFFICE

2,426,511

MECHANICAL ASH TRAY

Joseph Wilfrid La Pointe, Astoria, N. Y.

Application December 19, 1945, Serial No. 635,972

7 Claims. (Cl. 232—1)

1

This invention relates to new and useful improvements in a mechanical ash tray.

More particularly the invention proposes a mechanical ash tray which is particularly intended to be used in smoker cars of railroad trains, in busy clubs and restaurants, and other places where many people usually smoke. In places of this type it is not uncommon to see ash trays filled and overflowing on to the floor and the furniture in the vicinity.

The new mechanical ash tray, in accordance with this invention, is characterized by the fact that it will empty itself. It is proposed that the new ash tray have one or more cylinders into which ashes and cigarette and cigar butts may be deposited. It is proposed to construct these cylinders with removable bottoms. It is an object of this invention to construct said receptacles of hollow cylinders open at their top and bottom ends, and a wing-shaped blade closing the bottom ends of said hollow cylinders. It is proposed that said wing-shaped blade be movably mounted beneath the open bottom ends of said hollow cylinders so that in certain positions the blade closes the bottoms of the cylinders and in other positions it is free of the cylinders. A large main collection receptacle is provided beneath said cylinders to catch and hold the ashes, and cigar and cigarette butts which fall through said open bottom cylinders. It is contemplated to associate the wing shaped blade with means by which it is periodically moved through positions opening the bottoms of the cylinders for emptying and cleaning purposes and then to positions closing the bottoms of said cylinders.

More specifically it is proposed that the wing shaped blade be rotatively mounted. The drive means which is associated with the wing blade includes an intermittent drive capable of periodically causing the wing shaped blade to turn around 180°. During this motion the bottoms of the cylinders will be closed and opened.

Another object of this invention is to associate a friction clutch with the drive of the wing shaped blade so that if a foreign particle becomes jammed in between the side wall of a cylinder and the wing shaped blade, no damage will be done. The blade will merely stop rotating. When the foreign particle is removed the blade will automatically assume its correct position in respect to the intermittent drive, which maintains the blade in stationary positions closing the bottoms of the cylinders, until the drive rotates the blade periodically through angular distances of 180° during which time the bottoms of the cylinders will be open.

Another object of this invention is to associate a wiper with the wing shaped blade to act to wipe off the blade as it rotates. This prevents accumulation of ashes and dirt on the blade which in

2

time would jam the blade against the side of a receptacle.

The invention also proposes to associate a framework for supporting advertising signs with the drive of the wing shaped blade so that the advertising signs will be correspondingly moved. This is quite an attractive arrangement. It is also contemplated to provide suitable illumination for the advertising signs. For increased advertising space cellulose acetate film in roll form can be used in this space, using the same driving mechanism.

Still further the invention proposes the construction of a mechanical ash tray embodying the various features pointed out above which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary plan view of a mechanical ash tray constructed in accordance with this invention.

Fig. 2 is a fragmentary vertical sectional view taken on the line 2—2 of Fig. 1.

Fig. 3 is a fragmentary enlarged vertical sectional view taken on the line 3—3 of Fig. 1.

Fig. 4 is a fragmentary bottom view looking in the direction of the line 4—4 of Fig. 3.

The mechanical ash tray, in accordance with this invention, includes a casing 10 which is supported upon a base 11. Preferably the casing 10 is constructed of sheet metal. It is provided with a flat top wall 12 which is sunk a short distance below the top edge 13 of the casing. The top wall 12 is formed with one or more openings 14 beneath each of which a hollow cylinder 15 with open top and bottom ends is mounted. These cylinders 15 are attached to the bottom face of the top wall 12.

A wing shaped blade 16 is movably mounted beneath the cylinders 15 and in a certain position closes the bottom of the cylinders and in another position it will be free from said cylinders. In Figs. 1 and 2, the blade 16 is shown between the cylinders 15 so that they are free. When the blade 16 turns around 90° from the position it is illustrated in in Fig. 1 it will be in a position in which it closes the bottoms of the cylinders 15. The dot and dash lines 16' in Fig. 2 schematically indicates the latter position of the blade 16.

When said blade 16 closes the bottom ends of said cylinders 15 receptacles are formed for cigarette and cigar ashes and butts.

A large main collection receptacle 18 is located within the base 11 at a position beneath the cylinders 15. This large main receptacle 18 may

be removed from the bottom of the base 11, or may be removed in any other obvious way. A guide funnel 19 is mounted upon the top of the base 11 and extends upwards to a position beneath the cylinders 15 for guiding the ashes and cigarette and cigar butts down to the collection receptacle 18. The casing 10 has an opening 20 through which the guide funnel 19 extends. The top of the guide funnel 19 is located a short distance beneath the bottom edges of the cylinders 15. The wing shaped blade 16 is rotatively mounted. More specifically, it is mounted upon the top end of a vertical shaft 21. This shaft 21 is rotatively mounted on a housing 22 which in turn is supported on and by the guide funnel 19.

The wing shaped blade 16 is associated with means for periodically moving it from and to positions beneath the open bottom cylinders 15. This means is in the nature of a drive for the shaft 21. This drive includes a friction disc 23 fixedly mounted on said shaft 21 and cooperative with the side face of a gear 24 which is turnably mounted on said shaft 21. Resilient means, namely spring 26, urges the gear 24 against the friction disc 23. The disc 23 is provided with a friction gasket 25 against which the gear 24 engages. The spring 26 is mounted coaxially about the shaft 21, and acts against a collar 27 fixedly mounted on said shaft 21. The gear 24 is periodically driven by a drive transmission which includes an intermittent drive. This transmission is operated by a small electric motor 28 which is mounted within the housing 22.

The shaft 29 of the motor 28 extends through a bushing 30 which is mounted through the bottom wall of the housing 22. A nut 31 holds the bushing 30 in position. An intermittent drive pinion 32 is mounted upon the bottom of the shaft 29 and is cooperative with a four position intermittent drive wheel 33. This wheel 33 is rotative on the shaft 21. It is supported by a collar 34 which is fixedly mounted on the shaft 21 beneath the wheel 33. A gear 35 is fixedly mounted upon the top face of the four position intermittent drive wheel 33. The gear 35 meshes with a gear 36 which is fixedly mounted on a counter shaft 37 rotatively mounted on and through the housing 22. The top and bottom walls of the housing 22 are provided with bushings 38 through which the shaft 37 passes. These bushings 38 are held in position with nuts 39. A collar 40 is fixedly mounted on the shaft 37 and rests against the top face of one of the bushings 38. A large gear 41 is mounted upon the shaft 37 and meshes with the gear 24. The ratio of these gears are 2:1. A wiper 44 is fixedly mounted upon the bottom face of the wall 12. This wiper 44 has a rubber member 45 which extends across the top face of the wing shaped blade 16 when the blade is in the position shown in Fig. 1. The wiper 44 is located immediately adjacent the cylinders 15 and is for the purpose of wiping the top face of the blade 16 each time that the blade makes one revolution. The material wiped off of the blade 16 will fall down into the guide funnel 19 and then into the collection receptacle 18.

A sleeve 47 is rotatively mounted upon the shaft 21. This sleeve 47 has bearing 48 in its ends which engage the shaft 21. A framework 49 is mounted upon the top end of the sleeve 47. This framework consists of a hub portion 50 which is attached to the sleeve 47, a spoke or spider portion 51 which extends radially of the

hub 50 and which connects with a sign holder 52 for supporting advertising and other signs. This sign holder 52 extends around within the casing 10. The casing 10 is formed with one or more window openings 53 from which the sign holder 52 is viewable. An auxiliary advertising sign band 54 is mounted upon the sign holder 52. The casing 10 has additional windows 55 through which the auxiliary sign band 54 is viewable.

The hub 50 rests upon a washer 57 which in turn rests upon the top face of a bushing 58 which is mounted through the top wall of the housing 22. A nut 59 holds the bushing 58 in position. The shaft 21 passes through another bushing 58 which is mounted through the bottom wall of the housing 22. This latter bushing 58 is held in position by a nut 59. A collar 60 is mounted upon the shaft 21 and rests against the top face of one of the bushings 58. A gear 62 is mounted upon the sleeve 47 and meshes with a gear 63 mounted upon the counter shaft 37. Electric lamps 65 are mounted within the casing 10 and serve to illuminate signs mounted upon the sign holders 52 and 54.

The operation of the mechanical ash tray may be understood from the following:

The wing shaped blade 16 is normally in a position to extend across and close the open bottoms of the cylinders 15 when the intermittent drive four position wheel 33 is in a stationary position. Rotations from the motor 28 drives the intermittent drive pinion 32, and for each revolution it makes, it will turn the four position wheel 33 to a new position. The four position intermittent drive wheel 33 turns 90° each time. This motion is transmitted by the gears 35 and 36 to the counter shaft 37. A 90° turn of the counter shaft 37 indirectly turns the shaft 21 180° through the gears 41 and 24. This causes the wing shaped blade 16 to turn around 180°. During this motion the open bottom ends of the cylinders 15 will be free, and ashes and cigarette and cigar butts will fall through the funnel 19 and then into the main collection receptacle 18. Because the top wall 12 is at a lower elevation than the top 13 of the casing 10, the top portion of the casing is in the nature of a receiving cup for holding ashes, cigarette and cigar butts which are deposited in it. The ash tray can never assume an overflowing condition because periodically the cylinders 15 will automatically be emptied. The wiper 44 keeps the top of the blade 16 clean.

Rotations from the shaft 37 will also be indirectly transmitted to the sleeve 47 by the gears 62 and 63. Since the framework 49 is mounted on the sleeve 47 it will rotate correspondingly. This causes the advertising or other signs on the framework to be periodically moved and displayed through the window openings 53 and 55 of the casing 10.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. A mechanical ash tray, comprising a casing, a hollow cylinder with open top and bottom ends mounted on and accessible through an opening in

the top of said casing, a wing shaped blade movably mounted beneath said cylinder and in certain positions closing the bottom of said cylinder and in other positions being free of said cylinder, a main collection receptacle beneath said cylinder, a stationary housing mounted beneath said cylinder, a wing-shaped blade and not restricting passages of ashes, cigar or cigarette stubs and the like from said cylinders to said main collection receptacle, and motor driven means mounted in said housing and connected with said blade for periodically moving said blade alternately to said positions, including an intermittent drive.

2. A mechanical ash tray, comprising a casing, a hollow cylinder with open top and bottom ends mounted on and accessible through an opening in the top of said casing, a wing shaped blade movably mounted beneath said cylinder and in certain positions closing the bottom of said cylinder and in other positions being free of said cylinder, a main collection receptacle beneath said cylinder, a stationary housing mounted beneath said wing-shaped blade and not restricting passage of ashes, cigar or cigarette stubs and the like from said cylinders to said main collection receptacle, and motor driven means mounted in said housing and connected with said blade for periodically moving said blade alternately to said positions, including an intermittent drive, and a friction clutch located between said intermittent drive and the wing shaped blade.

3. A mechanical ash tray, comprising a casing, a plurality of hollow cylinders with open top and bottom ends mounted on and accessible through openings in the top of said casing, a wing shaped blade movably mounted beneath said cylinders and in certain positions closing the bottoms of said cylinders, a main collection receptacle beneath said cylinders, a stationary housing mounted beneath said wing-shaped blade and not restricting passage of ashes, cigar or cigarette stubs and the like from said cylinders to said main collection receptacle, and motor driven means mounted in said housing and connected with said blade for periodically moving said blade alternately to said positions.

4. A mechanical ash tray, comprising a casing, a plurality of hollow cylinders with open top and bottom ends mounted on and accessible through openings in the top of said casing, a wing shaped blade movably mounted beneath said cylinders and in certain positions closing the bottoms of said cylinders, a main collection receptacle beneath said cylinders, a stationary housing mounted beneath said wing-shaped blade and not restricting passage of ashes, cigar and cigarette stubs and the like from said cylinders to said main collection receptacle, and motor driven means mounted in said housing and connected with said blade for periodically moving said blade alternately to said positions, including an intermittent drive and a friction clutch located between said intermittent drive and said wing shaped blade.

5. A mechanical ash tray, comprising a casing, a plurality of hollow cylinders with open top and bottom ends mounted on and accessible through openings in the top of said casing, a wing shaped blade movably mounted beneath said cylinders and in certain positions closing the bot-

toms of said cylinders and in other positions being free of said cylinders, a main collection receptacle beneath said cylinders, and a guide funnel for guiding ashes, cigarette and cigar butts from said cylinders to said main collection receptacle, a stationary housing mounted beneath said wing-shaped blade and not restricting passage of ashes, cigar and cigarette stubs and the like from said cylinders to said main collection receptacle, and motor driven means mounted in said housing and connected with said blade for periodically moving said blade alternately to said positions.

6. A mechanical ash tray, comprising a casing, a plurality of open bottom cylinders mounted on and accessible through openings in the top of said casing, a wing shaped blade movably mounted beneath said cylinders and in certain positions closing the bottoms of said cylinders, and in other positions being free of said cylinders, a main collection receptacle beneath said cylinders, a stationary housing mounted beneath said wing-shaped blade and not restricting passage of ashes, cigar or cigarette stubs and the like from said cylinders to said main collection receptacle, and motor driven means mounted in said housing and connected with said blade for periodically moving said blade alternately to said positions, comprising, a main shaft rotatively mounted in said housing and connected with said blade, a friction disc mounted on said shaft, a gear turnably on said shaft, resilient means urging said gear against said friction disc, and a motor driven transmission including an intermittent drive for periodically turning said gear.

7. A mechanical ash tray, comprising a casing, a plurality of open bottom cylinders mounted on and accessible through openings in the top of said casing, a wing shaped blade movably mounted beneath said cylinders and in certain positions closing the bottoms of said cylinders, and in other positions being free of said cylinders, a main collection receptacle beneath said cylinders, a stationary housing mounted beneath said wing-shaped blade and not restricting passage of ashes, cigar or cigarette stubs and the like from said cylinders to said main collection receptacle, and motor driven means mounted in said housing and connected with said blade for periodically moving said blade alternately to said positions, comprising, a main shaft rotatively mounted in said housing and connected with said blade, a friction disc mounted on said shaft, a gear turnably on said shaft, resilient means urging said gear against said friction disc, and a motor driven transmission including an intermittent drive for periodically turning said gear, said main shaft being provided with a collar, and said resilient means comprising a spring coaxially about said main shaft and acting between said collar and gear.
